Primary Examiner — Derrick E Holland(74) *Attorney, Agent, or Firm* — Hovey Williams LLP(57) **CLAIM**

The ornamental design for a motor controller housing, as shown and described.

DESCRIPTION

FIG. 1 is a front perspective view of a motor controller housing showing the new design;

FIG. 2 is a rear perspective view thereof;

FIG. 3 is a front elevation view thereof;

FIG. 4 is a right side elevation view thereof;

FIG. 5 is a left side elevation view thereof;

FIG. 6 is a top plan view thereof; and,

FIG. 7 is a rear elevation view thereof.

The broken lines shown represent environmental subject matter and form no part of the claimed design.
